Primary Examiner — John Windmuller*Assistant Examiner* — John R Yeh(74) *Attorney, Agent, or Firm* — Stites & Harbison, PLLC; David W. Nagle, Jr.(57) **CLAIM**

The ornamental design for the remote control, as shown and described.

DESCRIPTION

FIG. 1 is a front perspective view of a remote control showing my new invention; FIG. 2 is a rear perspective view of the remote control of FIG. 1; FIG. 3 is a left side view of the remote control of FIG. 1; FIG. 4 is a right side view of the remote control of FIG. 1; FIG. 5 is a top view of the remote control of FIG. 1; FIG. 6 is a bottom view of the remote control of FIG. 1; FIG. 7 is a front view of the remote control of FIG. 1; and, FIG. 8 is a rear view of the remote control of FIG. 1. The broken lines in FIGS. 1-8 depict portions of the remote control that form no part of the claimed design.

1 Claim, 7 Drawing Sheets(56)
